US00D859467S

(12) United States Design Patent (10) Patent No.: US D859,467 S
(45) Date of Patent: * Sep. 10, 2019

(54) DISPLAY SCREEN OR PORTION THEREOF WITH ICON

(71) Applicant: Apple Inc., Cupertino, CA (US)

(72) Inventors: Sascha Höhne, Hamburg (DE); Ole Lagemann, Hamburg (DE)

(73) Assignee: Apple Inc., Cupertino, CA (US)

() Term: 15 Years

(21) Appl. No.: 29/659,780

(22) Filed: Aug. 13, 2018

Related U.S. Application Data

(63) Continuation of application No. 29/594,876, filed on Feb. 23, 2017, now Pat. No. Des. 828,855, which is a continuation of application No. 29/552,022, filed on Jan. 19, 2016, now Pat. No. Des. 782,516.

(51) LOC (12) Cl. 14-04

(52) U.S. Cl.

USPC D14/492

(58) Field of Classification Search

USPC D14/485-495

CPC G06F 3/0481; G06F 3/04817

(57) CLAIM

The ornamental design for a display screen or portion thereof with icon, as shown and described.

DESCRIPTION

The sole FIGURE shows a display screen or portion thereof with icon showing our new design.

The peripheral dashed broken lines illustrate a display screen or portion thereof, and form no part of the claimed design.

1 Claim, 1 Drawing Sheet
